(57) **CLAIM**

The ornamental design for a projection device with docking station, as shown and described.

DESCRIPTION

FIG. 1 shows a top, front, and left perspective view of a projection device with docking station showing our new design.

FIG. 2 is a top, rear, and left perspective view thereof.

FIG. 3 is a top and left perspective view thereof; and,

FIG. 4 is a top and right perspective view thereof.

The broken lines in Figures are for illustrative purposes only and form no part of the claimed design.

1 Claim, 4 Drawing Sheets

FIG. 2

FIG. 3

FIG. 4
